(57) **CLAIM**

The ornamental design for an animal resistant container, as shown and described.

DESCRIPTION

FIG. 1 is a front view an animal resistant container showing our new design;
FIG. 2 is a right side view thereof, the left side view being a mirror image;
FIG. 3 is a top view thereof;
FIG. 4 is a bottom view thereof;
FIG. 5 is a top front perspective view thereof;
FIG. 6 is a top front perspective view thereof; and,
FIG. 7 is a top front perspective exploded view thereof.
The broken lines in the drawings depict portions of the animal resistant container that form no part of the claimed design.

1 Claim, 7 Drawing Sheets
